 Maschinenfabrik Augsburg-Nürnberg A. G.,
 Nuremberg, Germany, a corporation of Germany

Application August 12, 1932, Serial No. 628,586
 In Germany August 15, 1931

2 Claims. (Cl. 61—22)

My invention relates to an operating device for head or top flaps of such weir closures as, for instance, roller weirs, lifting sluices, and the like, in which the flap is operated by two or more lifting rods engaging a bending-proof longitudinal supporting member forming a part of the flap on the tail side of the weir, each of said rods being connected with a crank shaft located within the body of the closing member of the weir.

With such arrangements the connecting line between the point of engagement of a lifting rod at the corresponding crank arm of the driving shaft and the point of engagement of said rod at the bending-proof supporting member of the flap extends in another direction than the middle plane of said supporting member which plane extends through the point of engagement of the lifting rod at the said member, said two directions varying continually while the flap is being moved.

From the diagram shown in Fig. 1 in which *a* denotes the fulcrum of the driving crank shaft, *b* the point of engagement of a lifting rod at a crank, *c* the fulcrum of the hinge of the flap, and *d* the point of engagement of the lifting rod at the bending-proof supporting member, it appears that the resolution of the forces in the supporting transverse section is such that the hinge joint of the flap must take up a great part of the supporting forces, this part varying continually while the flap is being moved, in consequence whereof it has heretofore been necessary to design said hinge in such a manner that it was able to stand the great strains and stresses to which it was exposed.

The object of the present invention is to completely eliminate these strains and stresses, and this object I attain by designing the lifting rods engaging the bending-proof supporting member of the flap also as bending-proof supporting members, and by connecting to each of them, at a moderate distance from its point of engagement at said flap supporting member, a link, the other end of which is supported at the weir closure body at a point, the distances of which from the hinge point of the flap and from the point of engagement of said link at the lifting rod are equal to the distances between the last-mentioned point and the point of engagement of the lifting rod at the flap-supporting member and between said last-mentioned point and the hinge-point of the flap.

The effects thereby obtained are that the supporting forces having heretofore acted upon the hinge axis of the flap are now being taken up by

the link, and as this latter has to take up chiefly tensile stresses, in that compressive stresses arise only when the flap has been turned down (they are only slight, as the amount of water with which the flap is loaded in that state is only small), it is possible to insert into the link a coupling nut permitting accurate adjustment of the link to that length which is most favorable for relieving the hinge of the flap.

The invention is illustrated diagrammatically and by way of example on the accompanying drawing on which Figure 1 shows the above mentioned diagram, while Fig. 2 is a side-view of the new arrangement and combination of parts constituting the invention, the parts being shown attached to a roller weir, the roller (*f*) of which is indicated merely by a circle. Fig. 3 is a horizontal longitudinal section along line III—III in Fig. 2, drawn to a smaller scale.

In the center of the weir roller *f* is located the torsion-proof hollow cylinder *g* which constitutes the driving shaft for the head or top flap *h*, which is stiffened by an internal bending-proof structure *i*. Near each end of the cylinder or shaft *g* is provided a crank arm *l* and each crank arm is connected at *j* with the flap *h* by a lifting rod *k* also designed as a bending-proof supporting member for the flap. Near its point of connection, or engagement with, the flap each rod *k* is pivotally connected with one end of a link *m*, the other end of which link is movably attached at *o* to a brace *e* in the roller *f*. The point of connection or engagement of each link *m* with the roller *f*, relative to the hinge of the flap and relatively to the point where each link *m* engages the corresponding lifting rod *k* or where this rod engages the stiffening structure *i* of the flap, is so located that the connecting lines of these points form an articulated parallelogram. A coupling nut *n* inserted into each link *m* allows of an accurate adjustment of the distance between the supporting point of the links from their point of engagement with the corresponding lifting rod *k* so that the hinge joints of the flap are relieved in all positions of the same.

I claim:

1. In a weir closure, the combination with the closure body, a driving shaft axially extending therethrough and crank arms secured to said shaft, of a head or top flap hinged to said closure body and an operating mechanism therefor, comprising a plurality of bending-proof lifting rods pivotally connected to said crank arms and to the supporting structure of said head or top flap, and

a corresponding number of links each pivoted to each one of said lifting rods at a short distance from the point of engagement of the rod with the supporting structure on said flap, the other 5 end of the link being pivotally supported on said closure body at a point, the distance of which from the hinge of said flap and from the point of engagement of the link with the lifting rod is equal to the distance between said 10 last-mentioned point and the point of engage-

ment of the lifting rod with the supporting structure of said flap and the hinge thereof respectively.

2. The combination as specified in claim 1, including a coupling nut in each of said links permitting accurate adjustment of the distance between the supporting point of said links and their point of engagement with their corresponding lifting rod. 5
